CLAIM

I claim the ornamental design for a support for GPS apparatus, as shown and described.

DESCRIPTION

FIG. 1 is a perspective view showing front, top and right side features of my new design;

FIG. 2 is a front elevation view thereof;

FIG. 3 is a rear elevation view thereof;

FIG. 4 is a right side view thereof, it being understood that a left side view is identical hereto but a mirror image reversal thereof;

FIG. 5 is a top plan view thereof; and,

FIG. 6 is a bottom plan view thereof.

The article is shown with a symbolic break in its length. The appearance of any portion of the article between the break lines forms no part of the claimed design.
